UNITED STATES PATENT OFFICE.

BERNHARD GLASER, OF CHICAGO, ILLINOIS.

LEAF-SUPPORTING MECHANISM.

1,116,054.

Specification of Letters Patent. Patented Nov. 3, 1914.

Application filed August 21, 1913. Serial No. 785,856.

To all whom it may concern:

Be it known that I, BERNHARD GLASER, a citizen of Germany, residing at Chicago, county of Cook, and State of Illinois, have 5 invented a new and useful Improvement in Leaf-Supporting Mechanism, of which the following is a specification.

My invention relates to loose leaf books and particularly to improved leaf supporting mechanism and arrangement.

Among the important objects of the invention are to provide strong yet flexible supporting members each in the form of a series of links pivoted together and overlapping; to provide improved means in the form of tongues on the book covers to which the ends of the supporting members are detachably secured; to provide improved means for detachably securing the supporting members to the tongues; to provide improved means for returning the supporting members to proper curvature when the book is closed; and in general to provide simplified and more efficient mechanism and arrangement of the character referred to.

In the accompanying drawings which clearly show the various features of the invention, Figure 1 is an end view of a closed book with the leaves broken away to reveal the supporting members. Fig. 2 is a similar view showing the book open, Fig. 3 is an enlarged side elevational view, partly in section, of one of the linked supporting members, Fig. 4 is a top view, partly in section, of the supporting members, and Fig. 5 shows a modified form of chain and arrangement for securing it to the tongues on the book covers.

The book shown comprises the covers 10 and 11 which at their score or hinge lines 12 and 13 have tongues or extensions 14 and 15. Connecting these tongues at intervals are supporting members M for the leaves L. Each of these supporting members comprises a series of links 16 pivoted together end to end. These links are preferably of sheet metal and of frusto-conical shape, the apex end of one being telescoped into the base of the other, pivot pins 17 passing 50 through the engaging apex and base ends as shown. The links overlap somewhat like fish scales so that the members are of smooth exterior to enable the leaves to pass readily thereover.

55 As shown in Figs. 1 to 4, the end links 16^a and 16^b may have holes 18^a and 18^b there-

through, the ends of these links passing through suitable openings 19 in the tongues 14 and 15 in order that the holes 18^a and 18^b may receive pins or rods 20 for engaging against the outer sides of the tongues to hold the supporting members in place. As shown in Fig. 5, the end links may have threaded extensions 21 for engaging through the tongue openings 20, nuts 22 engaging the extensions to clamp the members securely to the tongues.

The supporting members are first secured at one end to one of the tongues and the leaves L then applied thereto, the other ends of the members being then secured to the other tongue. When the book is opened the supporting members will bend upwardly and convex as shown in Fig. 2, and when the book closes these members should bend 75 downwardly and concave as shown in Fig.

1. To insure such concaving of the supporting members each member has connection with the back 23 of the book, each connection being in the form of a ring 2 freely receiving the member and anchored by a link 25 to the back 23 as shown. When the book is opened the leaves fall to the sides and convex the supporting members, and the connections also cause the back 23 to convex. 85 When the book is closed the back 23 straightens and concaves and by means of the connections pulls the supporting members back to concave form.

I thus provide very strong yet very flexible leaf supporting mechanism which can be readily applied and which is always held in position to give the book the proper shape.

I do not, of course, desire to be limited to the exact construction and arrangement shown as changes and modifications are possible which still come within the scope of the invention.

I claim the following:

1. In a loose leaf book the combination with the covers and back, of tongues extending from the covers, leaf supporting members detachably connected to and bridging between the tongues, and means connecting the members with the book back.

2. In a loose leaf book the combination with the covers and back of tongues extending from the covers, flexible leaf supporting members bridging between the tongues, and a ring on each supporting member, connected with the back.

3. In a loose leaf book the combination with the covers and back, of tongues extending from the covers, linked leaf supporting members bridging between and detachably connected with said tongues, and a ring receiving each member and connected with the book back.

4. In a loose leaf book the combination with the covers and back, of tongues extending from the covers, and leaf supporting members bridging between said tongues and each comprising a series of telescoped links pivoted together.

5. In a loose leaf book in combination

with the covers and back, of tongues extending from the covers, and leaf supporting members bridging between said tongues and each comprising a series of telescoped links pivoted together, and a ring receiving each member and connected to the book back.

In testimony whereof I have signed my name to this specification in the presence of two subscribing witnesses this 18th day of August, A. D. 1913, at Chicago, Illinois.

BERNHARD GLASER.
